UNITED STATES PATENT OFFICE.

EDWARD STERNS, OF ST. LOUIS, MISSOURI, ASSIGNOR TO EFFICIENCY OIL CORPORATION, OF WILMINGTON, DELAWARE, A CORPORATION OF DELAWARE.

VEHICLE-TIRE.

1,218,486.

Specification of Letters Patent.

Patented Mar. 6, 1917.

Application filed August 2, 1916. Serial No. 112,690.

To all whom it may concern:

Be it known that I, EDWARD STERNS, a citizen of the United States, and residing at St. Louis, in the State of Missouri, have 5 invented a certain new and useful Improvement in Vehicle-Tires, of which the following is a specification.

This invention relates to vehicle tires, and more particularly, to tires embodying a casing and an inner tube.

In vehicle tires as now constructed the casing is made sufficiently heavy to withstand the rough usage to which it is to be subjected; no attempt is, however, made to 15 make the casing itself air tight. The inner tube itself must, however, be air tight. Now any object, no matter how minute, which penetrates the casing will puncture the thin inner tube; moreover, any crack or cut in 20 the casing will cause the necessarily high pressure to blow a hole in the tube, and frequently rip open the casing. With the present type of clincher casings, pinching of the thin tube will frequently take place, thereby 25 damaging the same. The casing cannot be used to its limit of life on account of the frailty of the inner tube, and it is impractical to attach a shoe to the casing by sewing or nailing, as the presence of the seam inside 30 of the casing will abrade the tube and in a short time puncture the same. Moreover, a "flat tire" very often means the destruction of the casing. A vehicle is subject to side sway which will tend to rock the vehicle on 35 the tire, thereby causing the casing to be thrown against the rim, causing rim-cutting of the casing. Of course, the present inner tube cannot act as a reinforcement to the casing, but only performs the function of 40 an inflatable lining which carries the air. The result, therefore, is that the present vehicle tire necessarily has a short life.

Various attempts have been made to provide a vehicle tire, and more particularly, an 45 inner tube, the durability of which will be greater than the one now in use. These attempts have, however, been unsuccessful, for the reason that the true conditions and requirements were not understood and appreciated. An efficient and practical inner tube must possess the characteristics of resiliency, 50 expansibility, strength, simplicity, cheapness, lightness and durability, and should, moreover, reinforce the casing at the proper points. It must, moreover, be readily re-

movable from and replaceable in the casing, and must offer great resistance to puncturing and blow-outs. It should also, for commercial reasons, be adaptable to casings now in use.

Some of the objects of this invention are to provide a tube which, while possessing the desirable characteristics and qualifications, will be reinforced to possess great strength, and in such a manner as to close 65 up any puncture which may be formed, but so as not to impair the necessary expansion.

Further objects will appear from the detail description taken in connection with the accompanying drawing, in which:

Figure 1 is a section through a vehicle tire embodying this invention, and showing the tire inflated;

Fig. 2 is a section similar to Fig. 1, but showing the tire partially compressed;

Fig. 3 is a side elevation of the deflated inner tube; and,

Fig. 4 is a section on the line 4—4, Fig. 3.

In accordance with this invention the tube is constructed of an elastic material, such as 80 rubber, which has combined therewith layers of inelastic material, such as fabric strips, which extend circumferentially and transversely around the tube, and are disposed in axially spaced relation at the tread 85 to confine a layer of elastic material therebetween. In order to provide for the necessary expansion of the tube, the layers of fabric are arranged and adapted, as by interrupting these layers at the rim, so as to 90 permit such expansion, without, however, placing the elastic layer at the tread under tension. The tube is preferably thickened at the tread, and the layers of fabric preferably extend to the tire rim and past the 95 breaking lines of the casing.

Referring to the accompanying drawing, 1 designates a wheel felly provided with a rim 2 adapted to receive a casing 3. The wheel, rim and casing may be of any suitable construction, the casing being in this case of the clincher type.

The inner tube 7, provided with a valve stem 8 of usual construction, is, as in the application referred to, formed of a body material of inner tube rubber, or of a suitable material having the characteristics of rubber, and the wall thickness increases from the inner to the outer circumference of the tube. In accordance with this invention, 110

however, the body material has embedded therein a reinforcing material comprising, in this case, layers of tire fabric, such as Sea Island cotton. These layers of reinforcing material are arranged in spaced relation, with one layer near the inside and the other layer near the outside of the tube. In forming this tube, it can be made on a mandrel, the layers of rubber and fabric reinforcement applied successively, and the whole vulcanized together, or the tube may be formed on a tube machine. When formed, the rubber and reinforcement are joined together so as to form an integral structure.

An inner tube must, of course, be expandable so as to conform to and provide a suitable backing for the casing. Since, however, the fabric reinforcement is inelastic, and will not, therefore, stretch any appreciable amount, it is necessary to provide some means or construction whereby the tube is permitted to expand transversely. In the particular embodiment illustrated, the layers of reinforcing material are arranged to provide breaks or interruptions, and these breaks or interruptions are located at the inner circumference of the tube, where the tube is protected by the wheel rim. The result, therefore, is that this tube can expand at its inner circumference, at the same time leaving the sides and outer circumference reinforced and protected to the fullest extent.

The arrangement of the reinforcing layers in spaced relation in the body material, and the vulcanization of the body material and the reinforcement into an integral structure causes the imprisonment or confinement of a layer of rubber between the layers of reinforcing material. Now, if a sharp instrument should penetrate the outer layer 10, or in fact, penetrate the tube wall, then the layer of rubber imprisoned between the fabric layers will, on account of its integral attachment with the fabric layers, act to close the hole formed by the instrument when the instrument is withdrawn, or firmly hug the instrument so closely as to prevent the escape of air. This is on account of the fact that the rubber between the layers is not stretched, but is in its original condition and maintained so for the reason that the extension or stretch comes at the inner circumference, where the gap is formed in the layers of fabric, and where the tube is protected by the wheel rim. If the rubber at the exposed tread were placed under tension, then puncturing of the tube would cause an enlargement of the hole rather than a closing thereof. In accordance with this invention, however, the rubber between the fabric layers is neutral and will, therefore, retain its original condition during the life of the tube. The result, therefore, is that these layers of fabric

not only form a protecting armor, but also form a self-closing means for closing any hole which may be formed or produced in the wall of the tube. It will be noted that the layers of fabric 10 and 11 extend from the tire rim, that is, from points opposite the tire rim, transversely around the tread. These fabric layers, therefore, extend inwardly beyond the breaking lines of the tube and casing, so that breaking of the tube along the lines where the fabric terminates is obviated.

It will, therefore, be seen that a tire is produced which is practically puncture-proof, for not only is puncturing of the tube rendered exceedingly difficult, but a puncture, when formed, will be self-closing. It is, of course, only small pointed instruments, such as nails and the like, which are at all liable to penetrate this inner tube, as sharp instruments, which cut gashes, will never cut through both casing and tube. Such instruments will, at the most, only form gashes extending only partly into the tube, and which can, therefore, be repaired at leisure, as they permit the tube to be run for a considerable distance and for a considerable time without giving out. With all of its protective features against puncturing, the tube possesses the required resiliency and flexibility, as special means are provided for allowing free expansion of the tube under air pressure.

It is obvious that various changes may be made in the details of construction without departing from the spirit of this invention, and it is, therefore, to be understood that this invention is not to be limited to the specific details shown and described.

Having thus described the invention, what is claimed is:

1. In a vehicle tire, the employment of an inflatable inner tube of elastic material having combined therewith at the tread thereof layers of inelastic material disposed in axially spaced relation to confine the elastic material therebetween and adapted and arranged to permit transverse expansion of the tube, but prevent expansion of the confined elastic material at the tread substantially as and for the purpose set forth.

2. In a vehicle tire, the employment of an inflatable inner tube of elastic material having combined therewith layers of inelastic material disposed in axially spaced relation at the tread to confine the elastic material therebetween, said inelastic layers extending from the tire rim transversely around the tread, adapted to permit transverse expansion of the tube, but prevent expansion of the confined elastic material at the tread substantially as and for the purpose set forth.

3. In a vehicle tire, the employment of an inflatable inner tube of elastic material

having a thickened tread and having combined therewith layers of inelastic material disposed in axially spaced relation at the tread to confine the elastic material therebetween, said inelastic layers extending from the tire rim transversely around the tread, adapted to permit transverse expansion of the tube at the rim but prevent expansion of the confined elastic material at the tread, substantially as and for the purpose set forth.

4. In a vehicle tire, the employment of an inflatable inner tube of elastic material having combined therewith layers of inelastic material extending transversely around the tube and disposed in axially spaced relation at the tread to confine the elastic material therebetween, said inelastic layers being in-

terrupted at the rim and adapted to permit transverse expansion of the tube at the rim, substantially as and for the purpose set forth.

5. In a vehicle tire, the employment of an inflatable inner tube of rubber increasing in thickness from the tire rim to the tread and having embedded therein fabric strips extending transversely around the tube and disposed in axially spaced relation at the tread to confine the rubber therebetween, said fabric strips being interrupted at the rim and adapted to permit transverse expansion of the tube at the rim, substantially as and for the purpose set forth.

In testimony whereof I affix my signature this 8th day of July, 1916.

EDWARD STERNS.
